The ornamental design for a digital audio disc player with
radio tuner for automobile, as shown and described.

(30) **Foreign Application Priority Data**

DESCRIPTION

Mar. 22, 2011 (JP) D2011-006380

FIG. 1 is a perspective view of the front, right, and top of a
digital audio disc player for an automobile illustrating the
present design.

(51) **LOC (9) Cl.** **14-03**

FIG. 2 is a front view of the digital audio disc player for an
automobile of FIG. 1.

(52) **U.S. Cl.** **D14/157; D14/258; D14/505**

FIG. 3 is a rear view of the digital audio disc player for an
automobile of FIG. 1.

(58) **Field of Classification Search** D14/131,

FIG. 4 is a left side view of the digital audio disc player for an
automobile of FIG. 1.

D14/132, 137, 155, 157, 168-171, 188, 194,
D14/197, 198, 239, 257, 258, 496, 498-508;
455/90.1-90.3, 344-355; 369/6-12

FIG. 5 is a right side view of the digital audio disc player for an
automobile of FIG. 1.

See application file for complete search history.

FIG. 6 is a top view of the digital audio disc player for an
automobile of FIG. 1; and,

(56) **References Cited**

FIG. 7 is a bottom view of the digital audio disc player for an
automobile of FIG. 1.
